UNITED STATES PATENT OFFICE.

PEARL CORK AND DWIGHT NAGLEE, OF WESTON, WEST VIRGINIA.

COMBINATION WRENCH AND PLIERS.

No. 874,394.

Specification of Letters Patent.

Patented Dec. 24, 1907.

Application filed August 15, 1906. Serial No. 330,723.

To all whom it may concern:

Be it known that we, PEARL CORK and DWIGHT NAGLEE, citizens of the United States, residing at Weston, in the county of Lewis and State of West Virginia, have invented a new and useful Improvement in a Combination Wrench and Pliers, of which the following is a specification.

This invention relates to combination wrenches and pliers, the object being to provide a pair of pliers with an adjustable jaw so that they can be used either as pliers or as a wrench.

With this and various other objects in view, the invention consists in the novel features of construction, combination and combination of parts, hereinafter fully described and pointed out in the claims.

In the drawing forming a part of this specification:—Figure 1 is a side elevational view of my improved plier and wrench. Fig. 2 is a detail perspective view of a guide member. Fig. 3 is a detail perspective view of a portion of one of the handles. Fig. 4 is a side elevational view of the sliding jaw. Fig. 5 is a perspective view of the worm-gear. Fig. 6 is a section taken on lines 6—6 of Fig. 1.

In the drawing A indicates one of the handles which is provided with an enlarged aperture portion A', having a jaw A² projecting therefrom. A circular recess is formed in the enlarged portion A' in which the enlarged round aperture portion B' of the handle B, is preferably mounted on a pivot pin C.

The round portion B' is provided with an upwardly projecting perforated portion B², having a vertical groove B³, formed therein adjacent its forward edges which is cutaway forming one half of a guide-way for the purpose hereinafter described. A transverse groove B⁴, is formed in the upper end of the portion B' adjacent the groove and is provided with semi-round recesses B⁵ at its top and bottom. A perforated member D formed exactly like the portion B² is riveted to the portion B² by rivets E, and has a corresponding vertical groove D', cut away adjacent its forward edge forming the other half of the guide-way, in which the T-shaped tongue F', of the jaw F is slidably mounted which is provided with a rack edge F².

The member D is provided with a transverse groove D² having semi-round recesses D³, at its top and bottom, corresponding to the recess B³, forming sockets in which the

bearing lugs G', of a worm-gear G is mounted which works in the opening formed by the transverse grooves and meshes with the gear F² of the tongue F', so that the jaw can be opened and closed as desired. A notch A³, is formed in the edges of the portion A', and the enlarged portion B', is provided with a notch B⁶ forming a wire cutter.

The end of the jaw B carries a pivoted link B⁷ adapted to fit over a hook A⁴ formed on the end of the handle A, and hold the handles together.

From the foregoing description it will be readily seen that we have provided a pair of pliers so constructed that one of the jaws can be adjusted so as to enable the jaws to take hold of a small or large piece of material as desired.

Having thus fully described our invention, what we claim as new and desire to secure by Letters Patent is:—

1. The combination with a pair of handles provided with enlargements pivoted together, a jaw formed on the enlargement of one handle, an upwardly projecting portion formed on the enlargement of the other handle, a complemental member secured to said upwardly projecting portion, forming a guide-way, a jaw slidably mounted in said guide-way and means for adjusting said jaw, substantially as described.

2. The combination with a pair of handles, provided with enlargements pivoted together, of a jaw projecting out from the enlargement of one of the handles, an upwardly projecting portion formed on the enlargement of the other handle and provided with a groove, a complemental member secured to said upwardly projecting portion and provided with a groove, a jaw provided with a tongue having a rack edge mounted in the grooves of the said upwardly projecting portion and member, and a worm-gear mounted in said member and adapted to engage said rack tongue, for the purpose described.

3. The combination with a pair of handles provided with enlargements pivoted together, the enlargement of one handle fitting into a corresponding recess in the enlargement of the other handle, a jaw projecting from said recessed enlargement, an upwardly projecting portion formed integral with said enlargement fitting into said recess and provided with a vertical groove and a transverse groove, a complemental member secured to

- said upwardly projecting portion, a jaw slidably mounted in said upwardly projecting portion and provided with a rack, a worm-gear mounted in said transverse groove and 5 meshing with said rack of said jaw, substantially as described.
4. The combination with a pair of handles provided with enlargements pivoted together, the enlargement of one handle fitting 10 into a corresponding recess in the enlargement of the other handle, a jaw projecting from said recessed enlargement, an upwardly projecting portion formed on the enlargement fitting into said recess and provided 15 with a vertical groove and a transverse groove, a complemental member secured to

said upwardly projecting portion and also provided with a vertical and a transverse groove, a jaw provided with a T-shaped tongue mounted in said vertical grooves, a 20 rack formed on said tongue and a worm-gear mounted in said grooves, meshing with said rack, substantially as described.
